MAILBOX

Clifford J. Holdren, Charleston, W. Va., assignor
of one-half to Harry S. Brown, Charleston,
W. Va.

Application February 23, 1939, Serial No. 258,028

5 Claims. (Cl. 232—17)

This invention relates to the general class of deposit and collection receptacles and pertains particularly to an improved mailbox of the type designed for house use.

5 The primary object of the present invention is to provide a novel and improved form of letter or mailbox wherein a novel means is provided for facilitating the removal of mail therefrom, such removal being effected by the shifting of a bottom gate whereby the mail is permitted to drop from the box into the hand.

Another object of the invention is to provide an improved mailbox having an improved form of magazine and paper holding device whereby 15 such articles may be securely maintained in position until removed, such device being novelly designed and incorporated in the structure of the box.

A further object of the invention is to provide 20 in a mailbox, a new and novel letter slot and covering means therefor which is so constructed that the entrance of dirt, rain or other matter into the box will be effectively prevented while at the same time letters may be conveniently deposited in the box without requiring any particular or complicated manipulation of the letter slot cover means.

The invention will be best understood from a 25 consideration of the following detailed description taken in connection with the accompanying drawing forming part of this specification, with the understanding, however, that the invention is not to be confined to any strict conformity with the showing of the drawing but may be changed 30 or modified so long as such changes or modifications mark no material departure from the salient features of the invention as expressed in the appended claims.

In the drawing:

40 Fig. 1 is a view in perspective of the improved box embodying the present invention.

Fig. 2 is a sectional view taken on the line 2—2 of Fig. 1.

Fig. 3 is a detailed perspective view of the hinge 45 means for a lid of the box.

Fig. 4 is a fragmentary sectional view taken on the line 4—4 of Fig. 1.

Fig. 5 is a fragmentary sectional view taken on the line 5—5 of Fig. 2.

50 Fig. 6 is a fragmentary perspective view showing the method of coupling the horizontal gate with the side walls of the box whereby the gate may have oscillatory movement.

Referring to the drawing, the numeral 1 generally designates the box proper, which has as an

integral part thereof, a magazine holding member or apron which is generally indicated by the numeral 2, and which is attached to the box, as hereinafter more specifically described.

The box 1 has the usual front and back walls 3 and 4, respectively, and the narrow side walls 5. The lower part or bottom of the box is open to provide a mail discharge opening 6. The side walls at the lower ends are slightly rounded or convex, as indicated at 7', for the purpose hereinafter described, and the back wall 4 extends upwardly to an elevation greater than the front wall 3 and is carried forwardly a distance equaling approximately one-third of the width of the side walls to provide the top 7. The adjacent portions of the side walls are extended, as indicated at 8, to meet the ends of the top 7 and the forward edges of the side walls from the lower part of the extensions 8 are inclined forwardly and downwardly forming the sloping edges 9. The front wall 3 is turned inwardly at its upper end and carried toward the back of the box between the edges 9 of the side walls to which it is attached for a distance of approximately one-third of the width of the side walls, thus leaving an open area or slot 10 which joins with the forwardly directed opening 11 lying beneath the forward edge of the top wall 7.

This forward edge of the top wall is turned back and inwardly, as indicated at 12, and is provided with the edge recess or slot 13 in which engages a flange or edge extension 14 formed along the edge of a lid or cover plate 15, said flange terminating in tongues 16 which engage over the inturned portion 12 of the top wall in the manner illustrated, to provide a hinge connection for the cover or lid. This lid normally tends to maintain a vertical position by gravity and it is prevented, however, from assuming a perfectly vertical position by turning in a small portion of each side wall adjacent the top end of the part 8 thereof to provide a stop 17. The lower edge of the lid 15 comes to the bottom of the opening 11.

The top edges of the side walls 5 are formed with inwardly directed flanges 18 which extend across the ends of the opening 10 and each of these flanges at its forward end or adjacent the inturned upper end portion of the wall 3, is provided with a hinge slot 18'.

Mounted to cover the opening 10 is a substantially horizontal lid 19 which is divided into the upper opening covering portion 20 and the lower or forward portion 21, which latter portion serves in the nature of a counterbalance means to insure the closing of the part 20 with 55

respect to the opening 10. At each end there is formed in the edge of the lid 19 a hinge slot 19' corresponding with the slot 18', and these slots have locking connection, the portion of the flange 18 lying behind each notch 18' entering the notch 19' so that the cover or lid 19 may oscillate on the flange 18, the upper portion 20 of the lid when in closed position, bearing against the undersides of the flanges. The counterbalancing portion 21 lies normally upon the inturned top part of the wall 3 and in this way coats with the flanges 18 to limit the upward swinging movement of the portion 20.

In the formation of the box, the side walls 5 are cut so that after the flanges 18 are formed, there will be additional material at the inner edges of the flanges to be rolled back to form the guides 22. These act as guides for letters or other small articles of mail which are inserted into the box through the openings 18—11.

The lid 15 is suspended over and in slightly spaced relation with the top surface of the portion 20 of the lid 19, as shown in Fig. 2, and thus snow, rain or other matter falling against the lid 15 will drip off onto the lid 19 and flow forwardly to be guided away from the mail receiving openings 10 and 11.

Adjacent the bottom of the box, each side wall has secured thereto a trunnion or pivot pin 23. Disposed to extend over the open bottom 6 is a gravity controlled gate 24 at each end of which is an upwardly extending hanger ear 25 which is pivotally coupled with a trunnion 23. This gate 24 is slightly transversely arcuate and the curvature of the arcuate lower edges 7' of each side wall 15 is concentric with or struck from the pivot or trunnion 23 as is also the curvature of the gate. The back wall is extended down slightly below the bottom edges of the side walls so as to form an abutment against which the rear edge of the gate 24 engages as the gate swings to closed position.

The forward edge of the gate 24 is rolled under to provide the thumb rest 26 which facilitates swinging the gate to open position with the thumb of the hand in which the mail is caught as it slips from within the box.

In order to prevent any mail from working between the back wall and the rear edge of the gate, the back wall is provided with the longitudinally extending ribs or corrugations 27 which start at their upper ends flush with the surface of the back wall and gradually extend forwardly to a maximum height at their lower ends just short of the lower edge of the back wall so that the back edge of the gate can pass beneath the corrugations. These corrugations serve as a guide for the mail, causing it to move forwardly as it drops onto the gate.

The lower edge of front wall 3 has a portion extended forwardly and upwardly and rolled back upon itself as illustrated in Fig. 4, to provide the groove or channel 28 which, while it extends across the face of the box, is broken intermediate its ends for the purpose hereinafter set forth. This channel 28 constitutes a bearing for the lower edge of apron 2, which comprises the plate portion 29, forming the central part of the apron. This plate has formed integrally therewith adjacent its lower end the rearwardly extending side wings 30, each of which is provided with an arcuate slot 31 in which a pivot pin or trunnion 23 engages to limit movement of the plate when the latter is oscillated in the groove 28. The apron 2 provides a holding

means for magazines, papers or other large articles of mail which cannot be inserted into the box. The apron is swung outwardly to form a substantially V-shaped recess into which rolled magazines or papers may be placed and due to the resilient contact of the rolled portion 28 with the lower edge of the apron, the apron will be normally urged inwardly so as to grip and hold such inserted magazine or other article. The upper end of the plate extends slightly above the inturned top portion of the wall 3 and is curved or turned outwardly slightly, as shown, and this plate may carry upon its face a name-card holder 32 and a light spring 33 for "pick-up" mail.

The lower edge of the plate 29 is provided with a cut out area 34 into which extends a forwardly pressed portion 35 of the front wall 3, which portion is provided to receive a thin lock of the cabinet type which is provided with a swinging locking tongue 36 which may be swung downwardly to a vertical position for engagement in a slot 37 in the gate body 24, so as to hold this member from swinging to opened position.

In order that the mailbox may be conveniently supported for use, the side edges of the back wall may be provided with apertured ears 38 in the manner shown through which securing screws or nails may be passed.

From the foregoing, it will be readily apparent that in the use of the present box, mail may be easily inserted or introduced by placing the same against the portion 20 of the horizontally disposed lid 19 and pressing it downwardly, which action will effect the oscillation of this lid together with the inward swinging of the hanging lid 15. By providing the horizontal lid 19 so that it will maintain a slightly downwardly inclined position, it will be seen that rain and snow will be effectively shed from the top of the box.

When the mail is to be removed, it is merely necessary, if the lock is released, to place the thumb of one hand against the inner side of the thumb rest 26 and pull outwardly to swing the gate 24 while holding the fingers of the hand beneath the open lower end of the box so that the mail will drop from the box into the hand. The gate 24 will close by gravity when it is released.

The apron 2 will be normally maintained in vertical position by rolled out lower edge of the front wall which forms the channel 28, this rolled edge operating in the nature of a spring to maintain the apron vertical and its outward swinging movement will, of course, be limited by the trunnions 23 engaging in the slots 31.

What is claimed is:

1. A mail receiving receptacle, comprising a box, the box having a mail discharging opening, a gate disposed across said opening and including upwardly extending end suspension ears pivotally attached to the box whereby the gate will normally close by gravity, said box having a back wall extended downwardly beyond the arc of oscillation of the gate to provide a stop for the gate, and said gate having a thumb rest at its forward edge by which the oscillation of the gate to open position is facilitated.

2. A mail receiver, comprising a box having a mail discharging opening in the bottom thereof, a gate disposed over said discharging opening and including suspension ears pivotally attached to the box whereby the gate is caused to move by gravity to closed position over said opening, said

box having a front wall provided at its lower edge with an upwardly extending rolled portion across and against the under side of which said gate swings and forming a transverse groove, an 5 apron plate extending vertically of the box in front of said front wall and having its lower edge rockably supported in said groove and normally yieldingly held upright by said rolled portion, and coupling means between the apron and the 10 body of the box permitting limited oscillation of the apron with respect to the box.

3. A mail receptacle, comprising a box having means in its upper portion facilitating the deposit of mail thereinto, said box including front, back 15 and side walls, the box being open at its bottom and said side walls having their lower edges arcuate, pivot members carried by the side walls upon the radial centers of the arcuate lower edges thereof, a gate adapted to position across said 20 bottom opening and having end suspension members each provided with an aperture for the reception of a pivot member, said gate being transversely bowed to conform to the curvature of the side wall edges, the said gate being suspended from the suspension means to close by 25 gravity over said discharge opening.

4. A mail receptacle, comprising a box having means in its upper portion facilitating the deposit of mail thereinto, said box including front, back and side walls, the box being open at its 30 bottom and said side walls having their lower edges arcuate, pivot members carried by the side walls upon the radial centers of the arcuate lower edges thereof, a gate adapted to position across said bottom opening and having end suspension 35 members each provided with an aperture for the reception of a pivot member, said gate being transversely bowed to conform to the curvature of the side wall edges, the said gate being suspended from the suspension means to close by 40 gravity over said discharge opening, said front wall having a portion at the lower edge thereof

rolled outwardly and upwardly to form an upwardly directed channel across and against the under side of which said gate swings, the rolled portion of the wall being brought into relatively close proximity to the outer face of the wall, a 5 plate member disposed vertically adjacent the front wall of the box and having a lower edge rockably supported in said channel, the rolled portion of the front wall yieldingly engaging and constantly urging the plate toward the front wall, 10 and slotted ears integral with the sides of said plate and extending across the adjacent side walls and having said pivot means loosely engaging in the slots thereof.

5. A mail deposit receptacle, comprising a box 15 having an inlet, said box having opposite side walls each having a lower edge of arcuate contour, the box being open between said side walls for the discharge of mail, the box having a back wall formed to provide a plurality of flutes of 20 gradually increasing depth toward the lower edge thereof, a portion of said back wall extending downwardly beyond the edge of the fluted portion, the box having a front wall having a lower edge in the plane transversely of the box with 25 the lower edge of the fluted portion of the back wall, a door comprising a plate member having an over-all length greater than the width of the box and transversely bowed to correspond to the curvature of the convex edges of the side walls, 30 an arm at each end of said door extending longitudinally along the outer side of the adjacent side wall, means pivoting each arm to the adjacent side wall at a point constituting the radial center for the arcuate edge of the adjacent wall, 35 said door being limited in its rearward swinging movement by the said extended edge portion of the back wall, and means carried by the door facilitating its forward oscillation across the lower edge of the front wall. 40

CLIFFORD J. HOLDREN.
